UNITED STATES PATENT OFFICE.

BARNEY PREBLUDA, OF FALL RIVER, MASSACHUSETTS, ASSIGNEE OF ONE-HALF TO
ISIDORE CHERNOCK, OF BOSTON, MASSACHUSETTS.

METALLIC HEEL FOR SHOES.

Application filed October 6, 1920. Serial No. 415,026.

To all whom it may concern:

Be it known that I, BARNEY PREBLUDA, a citizen of the United States, and resident of Fall River, in the county of Bristol and 5 State of Massachusetts, have invented a new and useful Improvement in Metallic Heels for Shoes, of which the following is a specification, reference being had to the accompanying drawing, forming part thereof.

10 My invention relates to improvements in metallic heels for shoes, and has for its object to provide a heel comprising a hollow metallic heel member and a separate heel plate which may be independently secured 15 to the shoe bottom and securely coupled with said hollow metallic heel member for securing the latter to the shoe and for serving as an auxiliary heel within the heel member to relieve the latter of part of the load which 20 would otherwise be carried thereon.

Another object of the invention is to provide a heel designed substantially along the lines disclosed in my copending application filed as of even date hereof, and treats with 25 a modification of the type of heel disclosed in said copending application, as will appear more apparent by a reference thereto, the within described type of heel providing for a design which is more adapted for heavier 30 duty than the other type of heel.

Other objects and advantages of the invention will be gathered from the description following herein and considered in connection with the accompanying drawing 35 wherein the invention is shown embodied.

The terms employed herein are used in the generic and descriptive sense to designate the elements illustrated, and are therefore not primarily intended as terms of limitation.

40 Referring to the drawing:

Fig. 1 represents a longitudinal, sectional view taken through my type of heel shown secured and set with a shoe;

45 Fig. 2 represents a perspective view of the heel plate used in the heel shown in the preceding figure;

Fig. 3 represents an elevational view of said heel plate shown secured to a shoe;

50 Fig. 4 represents a plan view of the heel shown in Fig. 1, showing the heel plate set in secured relation therewith;

Fig. 5 represents a sectional view taken on line 5—5 on Fig. 1;

55 Fig. 6 represents a schematic development

of the heel plate shown in the preceding figures;

Fig. 7 represents a plan view of the heel plate shaped ready for use;

Fig. 8 represents a plan view of the heel 60 similar to that shown in Fig. 4, but shows the heel plate removed therefrom;

Fig. 9 represents a similar view to that shown in Fig. 4, but shows a modified type 65 of heel plate set therein; and

Fig. 10 represents a schematic development of the modified type of heel plate shown in Fig. 9.

Like numerals refer to like parts throughout the several views of the drawing. 70

The numeral 20 represents a hollow, shaped, metallic heel member which is preferably made of aluminum so as to reduce the weight thereof to a minimum. The heel 75 20 is preferably cast with the integral, transverse partition wall 21, which divides the hollow of the heel 20 and provides the upper and lower heel chambers 22 and 23, respectively, on either side of said wall 21. Said heel member may be shaped to conform to any of the different styles of heels, as the French heel shown in Fig. 1, with the outer and exposed surfaces enameled in any desired color and finished off to suit the requirements of the shoe with which the same 80 is to be associated. The top 24 of the heel is preferably thickened around the same to yield a substantial horseshoe-shaped flange for the shoe to bottom on, and to provide the side heel plate recesses or shouldered sections 25 and the front and rear end heel plate recesses or shouldered sections 26 and 27, as shown in Fig. 8, which yield a socketed opening for the heel. Said recesses are depressed sufficiently low to accommodate the 85 thickness of the heel plate to be hereinafter described, and form between them in the top of the heel member 20 the end and side abutting and plate locking lugs 28 and 29.

The lower heel chamber 23 is preferably 90 packed flush with a leather packing 30, as shown in Figs. 1 and 5, which is held securely set therein by the anchoring bolt 31 which reaches into the upper chamber 22 of the heel member through an opening 32 provided therefor in the partition wall 21. To said packing 30 may be affixed the tread lift 33 (whether leather or rubber) by suitable nails or screws 34, as shown in said Fig. 1. 95

35 represents the three-flange type of coup- 110

ling or heel plate which is employed with the heel member 20 shown in Figs. 1 to 7 inclusive. Said heel plate is of the saddle type and is provided with the side flanges 36 and the rear flange 37 which fit, respectively, within the side recesses 25 and 27 of the heel member 20 between the abutting lugs 28 and 29, as shown in Fig. 4, and in contour assume a horseshoe shape. Said plate is made of sheet metal stock, as sheet steel, for example, and is preferably punched out and shaped in the one operation, the flanges 36 and 37 thereof lying in the same plane and being provided with nail or clincher perforations or holes 38 by means of which said plate may be securely set and coupled with the shoe S as shown in Figs. 1 and 3. Said flanges are shaped to fit within the respective shouldered recesses provided therefor in the top flange of the heel member. Depending downwardly from the plane of said flanges are the side and end webs or petals 39 and 40, respectively, which support the coupling base 41 of the plate 35, which base carries the threaded coupling nut or nipple 42 permanently secured thereto by being brazed or soldered in position therewith.

Said coupling base 41 is preferably centrally disposed within said plate 35 and may be designed to project beyond the plane of the flanges of the plate 35 to reach down within the heel chamber 12 as deep as may be required and as close to the wall 21 as may be desired, with the threaded nipple aligned therein to receive the coupling bolt 31, as shown in Fig. 1.

35^a represents the modified or four-flange type of heel plate shown in Figs. 9 and 10, which is similarly designed to the three-flange type of heel plate heretofore described and shown in the other views of the drawing, but is additionally provided with a fourth or front flange 37^a which fits the front recess 26 provided therefor in the top of the heel member 20.

Said modified type of heel plate 35^a fits the heel member 20 in all other respects similar to that explained in connection with the three-flange type of plate, but obviously serves to strengthen the heel plate and its connection with the heel member.

Thus it is true in this case as in the heel disclosed in the above referred to co-pending application, that the peculiar relationship and association between the heel plate and the heel member permits the former to function therein as an auxiliary heel, serving to take part of the load thereon and directing it to the heel lift 33 through the medium of the coupling bolt 31. Wherefore, the

work of the hollow heel 20, which is cast thin and light, is greatly reduced and added life is afforded same.

It will thus be noted that the heel plate 65 may be made up rigid and yet be light in weight, and serves as a brace in the outer heel to reinforce the same and to assist in carrying the load subjected thereto. The heel plate, as herein disclosed, permits of 70 its being conveniently affixed to the shoe, and provides a ready and easy means for coupling the outer heel member to the shoe.

While the preferred embodiments of my invention have been described in detail, I 75 do not wish to be limited to the particular construction thereof, since various changes in the form, material, proportions and in the details of construction may be resorted to without departing from the spirit or scope 80 of the invention, heretofore described and claimed in the subjoined claims.

Having thus described my invention in detail, what I claim as new is:

1. A heel comprising an outer hollow and 85 shaped heel member having side and end plate seating recesses formed in the top wall thereof; an inner saddle shaped plate member adapted to set and project within the hollow of said outer member and provided 90 with independent side and end flanges adapted to respectively fit within the side and end seating recesses of said outer member for supportedly engaging said plate member therein; and means for clamping 95 said plate and said outer members in secured relationship.

2. A metallic heel comprising a hollow, heel-shaped outer member having a closed bottom and a top flange provided with a 100 series of inner shouldered sections interposed between abutting lugs formed in the same into side and end top flange for separating said shouldered sections; an inner heel member having a coupling base centrally disposed therein and provided with independently radiating side and end webs terminating respectively in outwardly disposed perforated flanges at the side and ends of the inner heel member, said flanges adapted to seat and fit within the aforesaid side and end shouldered sections of said outer heel member for supporting the coupling base within the hollow of said outer member; and a coupling member engaging with 115 said coupling base of said inner heel member and said closed bottom of said outer member for clamping the two members securely together to form a unit heel therebetween.

In witness whereof, I hereunto affix my 120 signature this 4th day of October, 1920.

BARNEY PREBLUDA.
